UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

REFRIGERATOR.

Application filed June 23, 1924, Serial No. 721,823. Renewed July 14, 1927.

This invention relates to a refrigerator, and is directed to a refrigerator in which the inner shell of stone material is cast-united to a moulded refrigerator front, the 5 said refrigerator front and inner shell being cast by means of one pouring.

Means are additionally provided for insulating the inner shell from the refrigerator front by breaking the heat conductivity. A 10 further object is to so construct a refrigerator front that it is possible to secure an outer wall structure to said front which may be held in spaced relation with respect to the inner shell to provide a space wherein 15 insulating material may be packed for insulating the two shells from each other.

In the drawings:

Fig. 1 is a sectional view through the mould showing how the refrigerator front 20 and inner shell may be cast-united together by one pouring operation.

Fig. 2 is a similar section after the cementitious material has been poured.

Fig. 3 is a perspective view of the refrigerator partly in section.

Fig. 4 is a perspective view of the outer wall structure which is to be secured to the refrigerator front.

Fig. 5 is a perspective view of the fibrous 30 insulating frame to which the inner shell and refrigerator front are cast-united.

Fig. 6 is a section on the line 6—6 of Fig. 3.

Fig. 7 is a detail section showing how the 35 back plate is secured to the inner shell and to the outer wall structure.

This refrigerator consists of a refrigerator front *a* which is provided with a plurality of door openings *b*. The inner shell 40 is designated *c* and is provided with a plurality of food chambers *d* and the ice chamber *e*.

Referring to Figs. 1 and 2, it will be seen 45 how the mould is assembled together. This mould comprises a base member *f* to which are bolted the side walls *g* of the outer mould box. The cores *h* are carried by the base *f* and are of such a size as to form the food chambers in the inner shell when the 50 pouring takes place.

A fibrous frame *i* is floated within the mould by means of screws or other fastening devices *j*. These fastening devices may be secured to the fibrous frame from the inside

of the mould as shown in the drawings. 55 Fastening devices *k* which are here shown as large-headed nails are partly driven into the fibrous frame and when the stone work is poured into the mould in a plastic condition the same flows around these fastening devices and securely keys the stone work to the said fibrous frame. This is more clearly shown in Fig. 2, which shows the stone work as being poured into the mould. Pouring holes *m* may be provided for in the mould so 60 that the stone may be poured into the interior of the mould which is to form the refrigerator front.

Bushings *n* are floated within the mould by means of the fastening devices *o*, so that 70 when the stone is poured these bushings will be embedded in the stone work of the refrigerator front.

To complete the refrigerator assembly an outer wall structure *p* of cast stone is secured to the refrigerator front, as will be now described.

Cast in the front wall of this outer structure are a plurality of bushings *q*, more 80 clearly shown in Fig. 6. The screws *r* may be inserted from the refrigerator front through the bushings *n* and screwed into the tapped bushings *q* which, when screwed down, will securely anchor the outer wall structure to the refrigerator front. The 85 position of the bushings *q* is such that the outer wall structure is held in spaced relation with respect to the inner shell. An insulating material *s* may be packed into the space between the inner shell and outer wall structure.

I provide the fibrous strips *t* which are cast united to the inner shell at the rear. The back plate *u* is secured to the inner shell and to the outer wall structure, as shown in Fig. 7, by means of the fastening devices *v* which are passed through the back plate and secured to the fibrous strip *t* which is cast united to the inner shell. The fastening devices *w* are passed through the back plate and secured to the fibrous frame *x* cast united into the outer wall structure.

With this construction the inner shell and the refrigerator front may be cast with one casting operation, the front and inner shell being thereby cast-united to the fibrous frame *i*, thereby forming the inner shell as a unit with the refrigerator front. Ob-

viously, the outer wall structure could be of fibrous material instead of a moulded stone material, as shown in the drawings.

What I claim is:

- 5 1. In a refrigerator, the combination of a moulded refrigerating front, a fibrous frame, and a moulded inner shell, the said inner shell and refrigerator front being cast-united to said fibrous frame.
- 10 2. In a refrigerator, the combination of a moulded refrigerator front provided with door openings, a fibrous frame member cast-united to said refrigerator front and provided with door openings of like size as the 15 openings in the refrigerator front, and a moulded inner shell provided with a plurality of food chambers and cast-united to said fibrous frame.
- 15 3. In a refrigerator, the combination of a 20 moulded refrigerator front, a moulded inner shell, and a fibrous insulating frame, the refrigerator front cast-united to one side of said frame and the inner shell cast-united to the other side of said fibrous frame.
- 25 4. In a refrigerator, the combination of a 25 moulded refrigerator front, a moulded inner shell cast-united thereto, an outer wall structure, and means for securing the outer wall structure to the refrigerator front in spaced 30 relation with said inner shell.
- 30 5. In a refrigerator, the combination of a 35 moulded refrigerator front, a moulded inner shell cast-united thereto, an outer moulded wall structure, and means for securing the wall structure to said refrigerator front in spaced 40 relation with respect to the inner shell.
- 40 6. In a refrigerator, the combination of a 45 moulded refrigerator front, a moulded inner shell cast united thereto, an outer moulded wall structure, means for securing the outer structure to the refrigerator front in spaced relation with respect to the inner shell, and an insulating material packed between the outer wall structure and said inner shell.
- 45 7. In a refrigerator, the combination of a 50 moulded refrigerator front, a moulded inner

shell cast-united thereto, an outer moulded wall structure provided with tapped bushings cast therein, and means passing through the refrigerator front for screwing into the tapped bushings to secure the outer wall structure to the refrigerator front in spaced relation with respect to the inner shell.

55 8. In a refrigerator front, the combination of a moulded refrigerator front, a moulded inner shell cast-united thereto, an outer wall structure secured to said refrigerator front in spaced relation with respect to the inner shell, and means for supporting the inner shell at the rear, said supporting means secured to both the inner shell and to the outer wall structure.

60 9. In a refrigerator, the combination of a moulded refrigerator front, a moulded inner shell cast-united thereto, an outer wall structure secured to the refrigerator front and held in spaced relation with respect to the inner shell, an insulating material packed between said inner shell and outer wall structure, and a back plate secured to both the inner shell and to the outer wall structure for supporting the inner shell at the rear in spaced relation with respect to the outer wall structure.

65 70 75 10. In a refrigerator, the combination of a moulded refrigerator front, a moulded inner shell cast-united thereto, means for breaking the conductivity of the heat between the said moulded inner shell and refrigerator front, an outer wall structure and means for securing the outer wall structure to said refrigerator front in spaced relation with respect to the inner shell.

80 85 90 11. In a refrigerator, the combination of a moulded inner shell of stone, a refrigerator front formed of plastic stone and a frame to which said inner shell and front are cast united for insulating the front from the inner shell.

In testimony whereof I have affixed my signature.

LLOYD G. COPEMAN.
